UNITED STATES PATENT OFFICE.

OWEN REILLY, OF NEW YORK, N. Y.,

GRATE-BAR.

SPECIFICATION forming part of Letters Patent No. 225,419, dated March 9, 1880.

Application filed October 23, 1879.

To all whom it may concern:

Be it known that I, OWEN REILLY, of the city, county, and State of New York, have invented certain new and useful Improvements 5 in Grate-Bars, of which the following is a specification.

An important object of my improvements is to preclude the warping of grate-bars or the webs thereof through excessive heating.

10 I construct a grate-bar of a web and independent detachable and removable fuel-surface sections of novel construction, with or without means for locking said sections to the web, and I provide the web with a socket 15 or sockets and the fuel-surface with a tongue or tongues which fit in the said socket or sockets, the said sockets being wider than the web, so as to prevent the fuel-surface from tilting, and preferably, also, larger than the said 20 tongues, and open at the bottom and top, so as to afford a free circulation of air round said tongues for keeping the web cool and supporting combustion.

In the accompanying drawings, Figure 1 is 25 a partly sectional side view of a grate-bar embodying my improvements. Fig. 2 is a perspective view of one of the fuel-surface sections, and Fig. 3 is a perspective view of the portion of the web of the grate-bar to which a section 30 of the fuel-supporting surface is secured.

Similar letters of reference designate corresponding parts in all the figures.

A designates what I term the "web" of the grate-bar, which, in other words, is the vertically-extending portion designed for sustaining the weight which may be imposed on the 35 grate-bar. It is provided at the ends with bearers *a*, for resting on the supports in the combustion-chamber, furnace, or fire-box, 40 where it is to be used, and has an uneven upper surface or edge composed of supporting or contact points *b*, on which the fuel-surface sections rest, and intervening spaces *c*, forming ducts or apertures through which air may 45 circulate.

B designates sections of the fuel-surface of the grate-bar. Though they may be of any desirable number they are shown as three only. They rest upon the upper side of the web *A*, 50 and, as here shown, are provided with tongues or shanks *d*, which enter sockets or ring-shaped

extensions *e*, with which the web is provided, and which are open at the top and bottom and wider than the web, so as to prevent the fuel-surface sections from tilting. The tongues or 55 shanks have no contact with said sockets, except such slight contact at the edges of the tongues or shanks as will preclude the longitudinal displacement of the said sections, a free circulation of air between the tongues and 60 sockets being otherwise afforded.

As shown, these sockets *e* of the web have at the upper edge supporting or contact points *b'*, sustaining the sections of fuel-surface laterally at some distance from the center, and therefore affording them great stability, and these 65 sockets have air-ducts *c'* between their supporting or contact points *b'*.

If desirable, the sections *B* of fuel-surface may be locked rigidly to the web *A*, and to 70 admit of this I have provided their tongues *d* with projections or hooks *f*, which may slip under lugs *g* projecting from the interior of the sockets *e*. When these hooks *f* and lugs *g* are employed it will be necessary to insert the 75 tongues *d* in the sockets *e*, and thereafter to slip the sections *B* sidewise to effect the engagement of the hooks *f* with said lugs *g*.

To prevent the slipping of the sections *B*, so that the hooks *f* will be disengaged from the 80 lugs *g*, I provide the sections on the under side with ribs or toes *h*, impinging against one side of the web *A*, and insert a key, *C*, between the side of the tongues *d* farthest from said ribs or toes *h* and the adjacent side of the 85 sockets *e*.

The sections *B* are, in this example of my invention, composed of three longitudinal ribs and transverse angular ribs converging toward the central longitudinal rib, and their 90 side and end edges are provided with lugs or projections for keeping the sections apart.

It will be seen that by my invention the fuel-surface sections are afforded a very stable support upon the web, and all parts are so constituted and arranged that a free circulation of air is produced at all parts thereof.

What I claim as my invention, and desire to secure by Letters Patent, is—

1. A grate-bar comprising the combination 100 of a web provided with an annular socket or sockets and a detachable and removable fuel-

surface provided with a tongue or tongues fitting in the aforesaid socket or sockets, the said socket or sockets being wider than the web proper and forming extended supports for the fuel-surfaces, preventing them from tilting, substantially as specified.

2. A grate-bar comprising the combination of a web provided with an annular socket or sockets and a detachable and removable fuel-
10 surface provided with a tongue or tongues fitting in the aforesaid socket or sockets, the said socket or sockets being wider than the web proper to afford an extended support for said fuel-surface, and the said web being provided upon its upper edge and around the upper edges of said sockets with isolated bearing-points for the fuel-surface, substantially as and for the purpose specified.

15 3. A grate-bar comprising the combination of a web provided with a socket or sockets
20

and a detachable and removable fuel-surface provided with a tongue or tongues fitting in the aforesaid socket or sockets, the said socket or sockets being open at the bottom and top, and being sufficiently wider than said tongues 25 to afford a free circulation of air through them around said tongues to support combustion and keep the web cool, substantially as specified.

4. The combination, in a grate-bar, of a web 30 provided with a socket, a detachable and renewable fuel-surface provided with a tongue fitting in the socket, a hook and lug for securing said parts together, and a key fitting between the socket and tongue and preventing 35 the disengagement of said hook and lug.

OWEN REILLY.
